UNITED STATES PATENT OFFICE.

SAMUEL LEON GERSON, OF PENNSGROVE, NEW JERSEY.

DESIGN FOR A DISPENSING STAND.

Application filed January 4, 1924. Serial No. 8,234. Term of patent 14 years.

To all whom it may concern:

Be it known that I, SAMUEL LEON GERSON, a citizen of the United States, residing in Pennsgrove, New Jersey, have invented a new, original, and ornamental Design for Dispensing Stand, of which the following is a specification, reference being had to the accompanying drawing forming part thereof, in which:

Figure 1 is a front elevational view of

a dispensing stand embodying my new design; and

Fig. 2 is a horizontal sectional view taken on the line II—II of Fig. 1 further illustrating the window in my dispensing stand.

I claim:

The ornamental design for a dispensing stand, substantially as shown.

SAMUEL LEON GERSON.
